FLOOR DRAIN FIXTURE

Aaron Matheis, Michigan City, Ind., assignor to
 Josam Manufacturing Company, Cleveland,
 Ohio, a corporation of Delaware

Application April 24, 1946, Serial No. 664,588

1 Claim. (Cl. 285—37)

1 The present invention relates to a floor drain fixture which is adapted to be imbedded in a concrete floor structure or the like for draining water and other liquids from the floor and directing the liquids into a sewer connection.

In providing drains for concrete floors, for example, it has been the practice when using drains with large grates to install the sewer connections and floor drains prior to pouring the concrete. Often, the level of the floor does not turn out to be correct for the drain elevation, and the floor must then be removed adjacent to the drain and the drain fixture disconnected from the sewer and then reconnected at the proper level and the floor patched. This is expensive and the patching of the floor usually ruins its continuous surface or monolithic and waterproof properties.

An object of the present invention is to provide a floor drain fixture that has a body portion that is adapted to be attached to a sewer connection and having a grate member associated therewith which may be easily adjusted relative to the body portion to raise or lower the elevation thereof to correspond to the finished floor surface and the grate member may also be adjusted so that its surface will lie in the same plane as the floor formed about the drain.

Another object of the invention is to provide floor drain fixture of the type referred to hereinbefore in which the fixture will support extremely heavy loads without damaging the mechanism by which the adjustability of the elevation of the grate is obtained.

Still another object of the invention is to provide a floor drain fixture such as that referred to hereinbefore in which the means for adjusting the grate also forms an auxiliary passageway for conducting water entering openings in the side walls of the drain fixture to the outlet of the fixture.

Other objects and advantages of the invention will be apparent from the following description of a preferred form of the invention, reference being made to the accompanying drawings in which:

Fig. 1 is a cross sectional view of a floor drain fixture showing the grate in the lowered position; and

Fig. 2 is a view similar to that of Fig. 1 but showing the grate in an elevated, tilted position.

Referring to the drawings, I have shown a floor drain fixture indicated generally at 10, which fixture comprises a bowl-like structure 11 that is open at its top and has an outlet 12 at the bottom thereof. The outlet is reduced in diameter 55

as compared to the upper portion of the structure and is adapted to be attached to a sewer pipe, not shown. The outlet 12 may be internally threaded for receiving a threaded sewer pipe, or as shown in the drawings, it may have an inwardly extending ledge 13 by which an inside caulk connection with the sewer pipe may be effected.

The bowl 11 which is preferably formed of cast iron, has a laterally extending, annular trough 15 formed integral therewith, which trough encircles the structure and is adapted to receive a water impervious sheathing member, not shown, which is clamped to the bottom wall of the trough by an annular clamping ring 16. The ring 16 is adapted to be pressed against the sheathing by screws 17 threaded in laterally extending clamps 18 secured under lugs formed on the bowl 11. The purpose of the sheathing is well known to those familiar with the art, and it extends laterally from the fixture and is imbedded in the floor so that any moisture seeping through the floor will be caught by the sheathing and directed into the trough 15. A plurality of openings 20, sometimes referred to as "weep" holes, 25 are formed through the walls of the bowl 11 and which open into vertical channels 19 formed in the inner surface of bowl 11 for draining the water from the trough 15 into the interior of the bowl 11 from whence it flows to the sewer.

On the interior of the bowl 11 there are formed spiral rolled threads 21, which threads are formed when the bowl 11 is cast and there is no machine operation required in the formation thereof. The rolled threads in cross section, as may be seen in the drawings, have rounded contours and the centers of the threads are spaced relatively wide apart.

A sleeve member 24, which is also of cast iron, is adapted to be threaded into the bowl 11 and 40 this member is provided with rolled threads 25 similar to those of threads 21, formed on the exterior of the sleeve. The threads are formed at the time the sleeve is cast by the formation of the mould. The sleeve 24 has a flange 26 extending 45 from around the top edge thereof and this flange engages the top edge of the bowl 11 when the sleeve is in its lowermost position. It will be apparent that by rotating the sleeve in the bowl, the elevation of the sleeve may be adjusted as desired and at the same time the threads will afford a bearing surface for the sleeve in the bowl of substantially 360°. Thus, although the sleeve 24 may be partially elevated, it will support a substantial load because of the heavy, thick threads on the bowl and sleeve and because of the

360° bearing surface between the sleeve and bowl.

As may be seen in the drawings, the threads 21 and 25 are adapted to fit loosely so that there will be a spiral passage 26 formed between the threads, which passages will empty into the bowl 11 at the outlet 12. By this arrangement, water from the openings 20 which does not pass downwardly through channels 19, due to clogging of the channels, for example, will drain down passage 26 into the outlet and the sleeve 24 will not interfere with this drainage although it extends over the openings 20.

In the form of the invention shown, an internal ledge 27 is formed about the central portion of the sleeve and projects inwardly. A grate member 28 which is in the form of a tubular member 29 having grate bars 30 over one end thereof, which bars are spaced from one another for affording drainage openings, and the other end of the member 29 is supported on the ledge 27. This form of grate member provides a maximum supporting strength and a maximum of open area for drainage between the grate bars 30. It will be understood, however, that any suitable grate bar member could be employed.

As brought out hereinbefore, the threads 21 and 25 fit loosely, and the sleeve 24 may be tilted axially with respect to the axis of the bowl. This is illustrated in Fig. 2 wherein line 35 represents the axis of the bowl and line 36 represents the axis of the sleeve. Thus, in the event the finished floor surface is not normal to the axis of the bowl, the sleeve may be canted to correspond to the floor level by a suitable shim 37.

When the drain fixture is installed, the bowl structure 11 is attached to the sewer connection at such an elevation that when the grate member sleeve 24 is in its midway position of its elevational adjustment, the top thereof will be level with the intended level of the floor surface. The concrete for the floor is then poured, and before the concrete has set it may be determined with certainty the exact level of the floor and if the top surface of the sleeve or the grate member 29 is found to be above or below the actual floor surface, the cement about the sleeve may be loosened and the sleeve adjusted to the proper level by turning it in the bowl. The wet concrete may then be smoothed around the drain fixture and when it hardens the grate member will be properly positioned and there will be no necessity of breaking up the hardened concrete for adjustment of the drain level.

It is to be understood that during this time the level of the grate member 29 can be adjusted as well as the elevation thereof by skinning the grate member, as explained previously.

By my invention I have provided a floor drain

fixture that is inexpensive to manufacture and one which has a grate that is adjustable as to elevation and which has provision for drainage through the elevating mechanism for the grate so that water collecting about the side of the drain fixture can be drained off into the fixture. Also, the means for adjusting the height of the grate member is rugged and will stand considerable weight without injuring the structure thereof in any way.

Although I have described but one form of the invention, it is to be understood that other forms might be adopted so falling within the scope of the claim as follows.

I claim:

A floor drain fixture comprising, a member having a tubular part for connection with a sewer pipe and a bowl formation extending above said tubular part, said formation having vertical side walls and a substantially greater diameter than said tubular part and having a flange extending radially outwardly from said side walls and located intermediate the top and bottom of the side walls of the bowl formation, the wall of the bowl structure having radial openings therethrough at substantially the level of the top of said flange, the inside of the side walls of the bowl structure having roll threads extending from top to bottom thereof and substantially entirely encircling the inside of the bowl, vertical channels in said threads and extending from in alignment with said openings, respectively downwardly to the bottom of said side walls; a sleeve having roll threads on the outside wall and being adapted to loosely fit into the threaded inside walls of said bowl formation whereby water passage along the threads may be effected and the sleeve may be tilted axially with respect to the bowl formation, said sleeve being extendable substantially entirely to the bottom of the inside walls of the bowl structure; and a grate member supported by said sleeve.
